UNITED STATES PATENT OFFICE

PAUL B. VALLÉ, OF NEW HAVEN, CONNECTICUT, ASSIGNOR TO THE CONNECTICUT HARD RUBBER COMPANY, OF NEW HAVEN, CONNECTICUT, A CORPORATION OF CONNECTICUT

DESIGN FOR A SERVING TRAY OR SIMILAR ARTICLE

Application filed July 14, 1932. Serial No. 44,321. Term of patent 7 years.

To all whom it may concern:

Be it known that I, PAUL B. VALLÉ, a citizen of the United States, residing in New Haven, in the county of New Haven and State of Connecticut, have invented a new, original, and ornamental Design for a Serving Tray or Similar Article, of which the following is a specification, when taken in connection with the accompanying drawing, in which—

Fig. 1 is a top plan view of a serving tray showing my new design; and Fig. 2 is a side elevational view of the same.

The ornamentation shown in one corner of the tray in Fig. 1 of the drawing, is continued around the tray.

I claim:

The ornamental design for a serving tray, or similar article substantially as shown and described.

PAUL B. VALLÉ.
